UNITED STATES PATENT OFFICE

PAUL H. NELSON, OF COLLINGSWOOD, NEW JERSEY, ASSIGNOR TO WESTINGHOUSE ELECTRIC & MANUFACTURING COMPANY, A CORPORATION OF PENNSYLVANIA

AMPLIFIER

Application filed April 4, 1930. Serial No. 441,603.

My invention relates to amplifying systems, and more particularly to systems for use in connection with phonograph pick-up devices, talking moving pictures and the like.

5 In devices of the type referred to above, it has been exceedingly difficult to obtain pure reproduction of musical tones. Very little trouble has been experienced in amplifying speech-modulated currents, as the range of 10 frequencies covered by the voice is more or less limited and lies within the most efficient portion of the amplifying characteristic of known commercial apparatus. Musical tones, however, spread over a band of frequencies much broader than that covered by 15 the voice and these frequencies, toward the limits of the audio frequency band, are, consequently, imperfectly amplified, thus producing a certain amount of distortion in the 20 amplifier output.

It is an object of my invention to provide an amplifying system capable of producing substantially uniform amplification over a wide range of frequencies.

25 Another object of my invention is to provide variable inter-stage coupling means whereby frequency-response curves of different desirable characteristics may be obtained.

Another object of my invention is to provide 30 an amplifier for utilizing screen grid tubes and having the characteristics set forth in prior statements respecting objects of my invention.

Another object of my invention is to provide 35 an amplifier having means for altering the frequency-response at low audio frequencies without appreciably affecting the response at high audio frequencies.

40 An additional object of my invention is to provide an amplifier circuit having means for altering the frequency response at high audio frequencies without appreciably affecting the response at low audio frequencies.

45 An additional object of my invention is to provide an amplifier circuit wherein either the high or low audio-frequency response may be altered without either appreciably affecting the other.

50 In the accompanying drawing, the single

figure is a diagram of apparatus and circuits embodying my invention.

A photo-cell-controlled circuit 1 is disclosed as comprising the input supply source for the amplifying stages 2 and 3 referred to above. Since practically any desirable circuit may be used in combination with my improved amplifier, a detailed description of the photo-cell circuits is not considered necessary. In lieu of the photo-cell-controlled 55 circuit, I might, for example, impress, across the input circuit of the amplifier, a voltage from a phonograph pick-up device or a radio set through a suitable impedance-matching transformer.

A source of potential 4 comprises the conventional A. C. rectifier and filter circuits for supplying D. C. potentials to thermionic-tube circuits, as well as A. C. of suitable potential for heating the cathodes of the amplifying tubes.

The specific embodiment of my invention is shown incorporated in the coupling arrangement provided between two stages of push-pull amplification for utilizing screen-grid tubes in the first stage.

The first stage comprises a pair of push-pull connected tubes 5 and 6 of the screen-grid heater type, such as the U. Y. 224 type tube, the filaments of which are supplied 75 from the heater coil 7 of the potential-supply source.

An input coil 9, inductively coupled to the output 11 of the photo-cell-controlled circuits, is connected between the grids of the push-pull connected tubes, the tube cathodes 13 and 15 being electrically connected, through a grid-bias resistor 17, to a point on said coil intermediate its extremities, which point is joined, by means of the conductor 21, to the low-potential side of the voltage-supply source.

A condenser 23 is provided to by-pass the resistor 17 to allow a free path for the high-frequency component of the space-discharge currents. The anodes of the tubes are connected to the high-potential side of the voltage-supply source through a resistance 25 of approximately 100,000 ohms and an induc- 95 100

tance 27 of approximately 4 henries, in series connection, as shown.

The screen grids are tapped off at a lower potential, the resistance 29 providing the required drop in voltage to obtain the proper screen-grid potential. Coupling capacities 31 and 33 of the order of .01 mfd. are provided for establishing an energy-transfer relationship between the output of the first 10 push-pull stage and the input of the second stage.

The second stage comprises a pair of three-element tubes of the power type, e. g., U. X. 250, in push-pull connection, the input circuit comprising an inductor 35 of approximately 5,000 henries joining the grids of the power tubes, a point 37 on the inductor being connected to the electrical center 39 of the filament circuit through a grid-bias resistor 41 and a by-pass condenser 43.

The filament current is supplied from a heating coil 45 of the potential-supply source. The primary of transformer 47 constitutes the output circuit of the power stage, a connection to the high-potential side of the voltage-supply source being made from a point 49 intermediate its extremities.

In using screen grid tubes in the amplifier, a very high impedance in the plate circuit is necessary because of the high impedance of the tubes, in order that a satisfactory output may be obtained. The use of inductive impedance was found to be entirely impractical as it would necessitate an estimated inductance of 2,000 henries or more to accomplish the desired condition. If such an inductance were utilized, the many turns of wire required in its construction would cause it to have such large distributed capacitance as to effectively short circuit it for all high frequencies. In addition to this effect, the variation of impedance of the reactor, as the frequency was changed, would cause the tubes to amplify non-uniformly with the varying frequency. One result of this phenomenon would be a loss of the low frequencies, as the reactor presents a low impedance at the low audio frequencies. A resistor also was found unsatisfactory. In both cases noted above, because of the high impedance, various stray shunt capacities permitted by-pass paths for the higher frequencies, with the result that the output-response curve of the amplifier was very low at the high-frequency end. 55 Very satisfactory results were obtained by reducing the value of resistance from about 250,000 ohms to approximately 100,000 ohms and inserting, in series therewith, an impedance of approximately 4 henries having very low distributed capacitance.

The above values assigned to the constants of my improved circuit will result in a substantially uniform response curve between the limits of 30 cycles and 8,000 cycles, which 65 practically covers the audio-frequency range.

It has been found desirable, at times, to change the characteristics of the response curve in a predetermined manner to compensate for acoustical defects of rooms or auditoriums. Should a particular auditorium be inefficient in its response to the high frequencies, it would be very desirable to be able to so change the response curve of the amplifier as to amplify the high frequencies to a greater degree than the others. 70 In my system, this can be accomplished by increasing the value of the reactors 27. A similar effect may be obtained on the low frequencies by so increasing the coupling capacities 31 and 33 that the coupling capacitors form a series resonant circuit with the reactor 35 across the grids of the amplifying stage. Therefore, by making the above elements of the amplifier variable, the response curve of the amplifier can be varied 75 to suit the conditions under which it is to be used.

While I have disclosed my invention in great detail, it is apparent that various changes may be made without departing from the scope of the invention and I do not desire to be limited to the specific details except in so far as shall be required by the prior art and by the appended claim.

I claim as my invention:

An amplifying system comprising a thermionic device of the screen grid type, an output circuit for said thermionic device, said output circuit having an impedance substantially equal to that of said thermionic device throughout a wide band of frequencies and comprising a resistor and a reactor having low distributed capacity; and an additional thermionic device, said last-mentioned thermionic device having an input circuit associated therewith and coupling means between said output circuit and said input circuit, said input circuit and said coupling means together forming a series circuit tunable to resonate at the lower audio frequencies.

In testimony whereof, I have hereunto subscribed my name this 26th day of March 1930.

PAUL H. NELSON.
